Garrettson Smith, Henry Brown, and
Joseph A. Read, of Philadelphia Penn^a
Assignors to

A. E. Warfield, of same place
Letters Patent No 758. Dated Jan. 22, 1856.

Ante-dated Dec. 31, 1855.

The schedule referred to in these Letters Patent and making part of the same.

To all whom it may concern:

Be it known that we Garrettson Smith, Henry Brown, and Joseph A. Read, of the city and county of Philadelphia, and state of Pennsylvania, have produced a new and original design for portable range cook stoves, and we do hereby declare that the following is a full, clear, and exact description of the same, reference being had to the annexed drawing forming part of this specification, in which

Figure 1. is a front elevation of the range. —

Figure 2. is an end elevation. —

Similar letters of reference denote the same part of stove, and design.

The front plate A. bears the doors B. and C. and ash hole covering D. On the right of door B. is an ornament in bas-relief composed of scrolls arranged and having the configuration set forth in fig. 1. —

The doors B. and C. are raised above the surface of the plate by moldings E. made up as shown in figure 2. and the panels embellished with the ornaments G. and H. in bas-relief. The former is made up of the dished scrolls e, f, g. having the foliage h. and i. sweeping gracefully from the sides of the ornament towards the corners of the panel. The surface k. of the ornament slopes outward towards the surface of the panel and is bounded by the wavy edge l; upon it are the projections m. The scrolls f. and g. merge into the figure m. filling the enclosure formed by the three scrolls, the entire configuration and arrangement being as fully set forth in the drawing. The ornament H. is made up of scrolls p. sloping surface q. and figure r. arranged and configured as shown in figure 1. —

The ash hole cover D. has the usual draft openings & is embellished

Des. 758

394
at each end with sweeping foliage; the arrangement and configuration being as shown in the drawing. —

The end plates P. have each a raised panel bearing an ornament in bas-relief, composed of scrolls, foliage and curved surfaces similar to the ornaments G. & H., the precise design configuration and arrangement being as shown in fig. 2. —

The foot R. is of the form shown in the drawing, having the projections t. in front, and on each side of the upper portion the foliage u. the lower portion terminating in a paw. —

What we claim as our production is the design configuration and arrangement of the ornaments in bas-relief and moldings on the several plates, as described and represented in the annexed drawing. —

In testimony whereof we have signed our names before two subscribing witnesses.

W. H. Utneper.

J. C. Brazer.
